CLAIM

The ornamental design for a clip box, as shown.

DESCRIPTION

FIG. 1 is a perspective view of a clip box showing my new design;

FIG. 2 is a front view thereof;

FIG. 3 is a side view thereof;

FIG. 4 is a top view thereof; and,

FIG. 5 is a bottom view thereof.

The broken lines in FIG. 5 indicate a boundary of the claimed design, within which no subject matter is claimed.
